UNITED STATES PATENT OFFICE.

WINFIELD P. PEMBROKE, OF ROCHESTER, NEW YORK.

EXPLOSIVE-ENGINE.

1,036,321.

Specification of Letters Patent. Patented Aug. 20, 1912.

Application filed August 12, 1909. Serial No. 512,619.

To all whom it may concern:

Be it known that I, WINFIELD P. PEMBROKE, of Rochester, in the county of Monroe and State of New York, have invented certain new and useful Improvements in Explosive-Engines; and I do hereby declare the following to be a full, clear, and exact description of the same, reference being had to the accompanying drawings, forming a part of this specification, and to the reference-numerals marked thereon.

My present invention relates to gas or explosive engines and it has for its object to provide such a motor which may be operated either on the principle of a four-cycle or a two-cycle engine, in the sense in which this term is employed in this art, at the will of the operator and which is capable of being converted during its operation from one type of engine to the other.

To these and other ends the invention consists in certain improvements and combinations of parts all as will be hereinafter more fully described, the novel features being pointed out in the claims at the end of the specification:

In the drawings: Figure 1 is a side elevation of a multicylinder engine illustrating one embodiment of my invention. Fig. 2 is a top plan view thereof, and Fig. 3 is a vertical sectional view taken on the line 3^x-3^x of Fig. 2. Fig. 4 is a similar view on the line 4^x-4^x of the same figure.

Similar reference numerals in the several figures indicate similar parts.

It is a well known fact that both the four-cycle engine and the two-cycle engine possess distinctive advantages and it is the object of my present invention to provide a motor which may be alternately operated as an engine of either class, thus permitting the desirable qualities of each to be brought into play at such times as they may be most effective.

In illustrating my invention I have shown a multicylinder engine comprising the cylinders 1 and 2 mounted upon the hollow crank case 3 with which their lower ends communicate, said case being divided by a transverse partition 4 into separate chambers into which the explosive mixture is introduced through intakes or feed pipes, such as 5 leading from a suitable carbureter. Each cylinder is provided with the usual piston 6 and these are each connected

by a piston rod 7 with the wrist pin 8 of the respective cranks 9, on the driving shaft 10, which is supported in suitable bearings and at one end is provided with the fly wheel 11. The cylinders are also provided with the exhaust ports 12 which open outwardly from the cylinders at points above the pistons, when the latter reach the limit of their outward movement. Intake passages 13 are also provided in the cylinder walls, their upper ends 14 entering the sides of the cylinders opposite the exhaust ports in proximity to the walls or baffling plates 15 on the ends of the pistons, while their lower ends, indicated by 16, communicate with the lower ends of the cylinders beneath the piston heads and thus when the latter are retracted open communication from the crank case chambers to the interior of the cylinders above the piston heads. At a suitable point between the ends of the intake channels 13, the walls of the cylinders are enlarged, as indicated at 17, and formed therein are cylindrical recesses within each of which is contained a rotary valve head 18, these heads in the different cylinders being mounted on a rotary shaft 19, which is driven in timed relation to the rotary movement of the crank shaft, so that at predetermined intervals, the intake channel 13 will be closed.

The means I have shown for accomplishing the last mentioned object, comprises a double set of driving connections or operating devices arranged between the valve shaft 19 and the driving shaft 10 which are alternately brought into play when the motor is being operated as a two-cycle or four-cycle engine. As a simple form of operating connections I have shown sets of gears which may alternately be brought into play, those comprising the two-cycle set consisting of the gear wheel 20, an idler 21, journaled on a stud shaft 22, and the gear wheel 23 attached to the driving shaft 10. The four-cycle set comprises the gear wheel 24 and the pinion 25, which is connected by the sleeve 26 to the gear wheel 21 which is constantly rotated by the gear wheel 23. The first mentioned set of gears 20, 21 and 23 are so proportioned that the valve shaft 19 will be rotated one complete revolution for each revolution of the driving shaft to attain the object of positioning the valves 18, as shown in the sectional view Fig. 3,

and opening the intake passage 13 of each cylinder when their respective pistons reach the limit of their outward movement. The other train of gear wheels 24 and 25 are 5 of such diameter that a complete revolution of the shaft 19 occurs only once for each two revolutions of the driving shaft 10.

The gear wheels 20 and 24 are journaled loosely on the shaft 19 and on their proximate faces are provided clutch teeth which coöperate with corresponding projections or teeth on the ends of a clutch sleeve 27 which is keyed to the shaft 19 and may be adjusted longitudinally to alternately engage with 15 one or the other of said gear wheels. The gear wheel 20 is provided with a single clutch tooth 28 with which coöperates the corresponding single tooth 29 on the adjacent end of the clutch sleeve, this arrangement of the single teeth being provided to insure the proper positioning of the shaft 19 when the engine is working on the two-cycle principle so that the valves on such shaft will always be in a proper position in 20 relation to the movement of the pistons in the various cylinders. It will be noted that when the engine is operated on the four-cycle principle the shaft 19 only makes one complete revolution for each two revolutions 25 of the driving shaft and it is for this reason that the gear wheel 24 is provided with two clutch teeth 30 (only one of which is shown) and the engaging face of the clutch sleeve is provided with dual coöperating projections or teeth 31. This arrangement of the 30 single coöperating teeth on the gear wheel 20 and one end of the clutch sleeve and the double provision of clutch teeth on the gear wheel 24 and the other end of the sleeve insures 35 the proper positioning of the valves 18 in respect to the pistons irrespective of what point in the stroke of the pistons the clutch sleeve may be thrown from engagement with one gear wheel into engagement 40 with the other. Both gear wheels are constantly rotating in the same direction and when adjustment of the sleeve takes place the momentum of the valve shaft 19 merely decreases slightly, during a partial revolution, until the tooth, or teeth, of the operating gear wheel engages those of the sleeve.

The cylinders are closed at their upper ends by the usual heads 32 and in each of these is arranged the exhaust passage 33 normally closed by a puppet valve 34 which is adapted to be opened inwardly and is supported on the valve stem 35. The latter is normally elevated by a spring 36 to hold the valve against its seat to close the exhaust 55 passage. The valves 34 are inactive when the engine is operating on the two-cycle plan, but they are brought into action when the engine is operating on the four-cycle principle by timing connections actuated periodically with reference to the movement of

the piston heads 6. These operating connections are so arranged that they may be thrown into and out of action at the will of the operator when he desires to convert the engine from one type to another. As 70 one means of controlling the valves 34 I have shown levers 37 journaled at 38 on the upper ends of guide members 39 which are supported for vertical movement in tubular columns 40 rigidly secured to the cylinder 75 heads 32. Each of the members 39 is moved upwardly or projected by means of a spring 41 bearing against its lower end, its movement being limited by a laterally projecting pin or projection 42 which extends outwardly through an elongated slot or aperture in the column and supports an anti-friction roller 43 with which coöperates the inclined or cam surface 44 on a longitudinally movable controlling bar 45, held in 80 place beneath a strap or guide block 46. The upper edge of the bar engages a shoulder 47 on the column, preventing its upward movement, but when the bar is shifted the cam surface 44 thereon engaging the roller 42 90 will cause the guide member 39 to be depressed against the tension of the spring 41 to position the pivot of the valve operating lever 37 in such position that when the lever is rocked in one direction the valve 34 will 95 be opened. When the engine comprises a plurality of cylinders, the controlling bar 45 extends over the top of each of them and is similarly guided on each of the columns and provided with cam surfaces which simultaneously depress and release each of the several guide members, as will be understood.

A rocking motion is imparted to the valve operating levers 37 by means of thrust rods 105 48 coöperating with their outer ends, and supported in suitable guides 49 and carrying at their lower ends rollers 50 which operate with cams 51, mounted on the shaft 19, said cams being set to open and close the 110 exhaust valves 34 of their respective cylinders during the alternate outward reciprocation of the pistons. The cams 51, of course, bear certain relative positions in respect to the valve 18 and are rotating constantly causing the rods 48 to reciprocate, but as the valve operating levers 37 are elevated when the engine is operating as a two-cycle engine, the valves 34 remain closed.

As it is essential that the exhaust valves in 120 the cylinder heads be brought into operation whenever the engine is converted into the four-cycle type and likewise, thrown out of operation when it is operating as a two-cycle motor, provision is made for shifting the controlling bar 45 simultaneously with the movement of the clutch sleeve 27 from engagement with one of the gear wheels 20 or 24 into engagement with the other. As one means of accomplishing this object in a 130

simple manner, I have shown a lever 52 which may be pivoted on a bracket 53 and provided at its lower end with a pin 54 resting in the annular channel of said sleeve, the lever at its upper end being provided with an elongated slot receiving the pin 55 on the bar 45.

The engine cylinders and their heads may be provided with the usual means for cooling them, such as the water jackets shown and they are also provided with a suitable igniting device, such as a sparking plug 56.

In Fig. 1 of the drawings the clutch sleeve 27 is shown in engagement with the gear wheel 24 and the controlling bar 45 thrust forwardly causing the depression of the members 39, this being the position the parts assume when the engine is operating on the principle of a four-cycle motor. The gear wheel 24, it will be remembered, is rotated one revolution for each two complete revolutions of the driving shaft 10, and in Fig. 3 the piston head 6 of one of the cylinders is shown retracted, and the valve 18 in position opening the channel 13. This is the intake stroke, the carbureted mixture being permitted to pass from the crank chamber, where it is under compression, into the cylinder. The upward movement of the piston 30 and the piston head closes the ports 14 and 12 compressing the explosive mixture in the top of the cylinder until it is ignited when its force drives the piston downwardly when it again uncovers the ports 12 and 14. During this stroke the intake passage 13 is closed by the rotation of the valve 18 and as the piston head begins to rise, the valve head 34 is opened by means of the cam 51 permitting the exhaust gases to find exit 40 through the passage 33. Upon the next reciprocation of the piston head the valve 34 is closed and the rotary valve 18 again brought into the position shown in Fig. 3, permitting another charge of explosive mixture to pass into the cylinder.

The operator desiring to convert the engine into a two-cycle motor shifts the lever 52, disconnecting the clutch from the gear wheel 24, and throwing it into engagement 50 with the gear wheel 20, and as this movement retracts the controlling bar 45, the members 39 supporting the levers 37 are released and projected upwardly by the springs 41 carrying the levers out of operative engagement with the valve stems 35. Now, the gear wheel 20 is rotated in unison with the driving shaft and upon each rotation of the latter the valve head 18 opens the intake passage 13, as shown in Fig. 3, permitting the carbureted gases to rush into the cylinder upon each outward movement of the piston head, where they are deflected upwardly by the baffling plate 15 to displace the previously exploded charge which is 60 driven outwardly through the exhaust pas-

sage 12, causing the scavenging of the motor to occur at precise intervals in the cycle of its operation.

A motor embodying my invention comprises but few parts which are simple in construction and by the arrangement of the parts as comprehended in my invention, I am enabled to produce a motor capable of being instantly converted from one type of engine to the other and in a single engine I 70 combine the advantageous features of both types, as it is possible to operate the engine so as to obtain an explosion upon each revolution of the driving shaft and obtain approximately twice the power effect per cylinder as compared with the four-cycle motor, at such times as the maximum power may be required, also I can cause the engine to operate as a four-cycle motor when it is desired to obtain a high speed of rotation of 80 the driving shaft with the flexibility of control possessed in such a motor, especially when constructed with a plurality of cylinders.

I claim as my invention:

1. In an explosive engine, the combination with a cylinder having an inlet and an exhaust port, a piston reciprocating in the cylinder and a driving shaft connected thereto, of a valve controlling the inlet port, 90 a supplemental exhaust port and a valve normally closing it, of means for opening and closing the inlet and exhaust valves, two sets of driving connections, one for actuating the valve operating means to open 95 and close said valves upon every reciprocation of the piston, the other for actuating the valve operating means to open and close said valves upon alternate reciprocations of the piston, and means for alternately connecting said driving connections with the driving shaft.

2. In an explosive engine, the combination with a cylinder having an inlet and an exhaust port communicating therewith near 110 its lower end, a piston reciprocating in the cylinder and alternately opening and closing said ports, of an auxiliary exhaust port, a valve for closing it and a valve for controlling the inlet port, devices operating said valves to open and close the inlet and auxiliary exhaust ports, a valve operating mechanism for actuating said devices upon each reciprocation of the piston, a similar mechanism for actuating 120 said valve operating devices upon alternate reciprocations of the piston, means for alternately connecting said mechanisms with the driving shaft and means for throwing the exhaust valve out of action during the 125 time the inlet valve is being operated by one of said mechanisms.

3. In a two cycle explosive engine comprising a cylinder having a piston and a crank shaft connected thereto and provided 130

with inlet and exhaust ports which are opened and closed by the piston, an exhaust port at the outer end of the cylinder and a valve controlling it, a separate valve controlling the inlet passage, means for opening and closing said valves, two sets of driving devices for actuating said means to operate the valves relatively to the movement of the piston and at different cycles, and a member 10 for connecting one or the other of the driving devices to the valve opening and closing means.

4. In an explosive engine comprising a cylinder having a piston therein and a 15 crank shaft connected thereto and provided with inlet and exhaust ports entering the sides of the cylinder and controlled by the piston for effecting a two-cycle operation of the engine, an auxiliary exhaust port leading 20 from the cylinder having a valve for closing it, a separate valve for controlling the inlet port and means for opening and closing said valves, two sets of driving devices each adapted to independently operate 25 said valve opening and closing means to actuate the valves relatively to the movement of the piston and at different cycles, and a member for effecting a driving connection between either of the driving devices and valve opening and closing means.

5. In an explosive engine, the combination with a connected cylinder and crank case, a piston, a crank shaft connected thereto, said cylinder being provided with an 30 inlet port leading thereto from the crank case and an exhaust port leading from the cylinder both arranged to be controlled by the movement of the piston, of an auxiliary exhaust port leading from the cylinder having a valve normally closing it, a movable valve arranged in the inlet port, means for opening and closing said valves, two-cycle driving devices for actuating said means to open said inlet port upon each reciprocation 35 of the piston, four-cycle driving devices for actuating said means to open said inlet port and auxiliary exhaust port valve upon alternate reciprocations of the piston, means for alternately connecting said two and four- 40 cycle driving devices with the means for opening and closing said valves, and a controlling member for rendering the exhaust port valve either effective or ineffective.

6. In an explosive engine, the combination 45 with a cylinder having inlet and exhaust ports and provided with a piston and crank shaft, of an auxiliary exhaust port in the cylinder, a valve normally closing it and a valve controlling the inlet port, a shaft connected to the inlet valve, two sets of driving devices between the valve shaft and driving shaft, one for causing the opening of the valve upon each rotation of the driving shaft and the other for causing it to be 50 opened upon alternate rotations of said

shaft, a clutch coöperating with said sets of driving devices connecting one or the other of them to the valve shaft, devices actuated by the latter for opening the auxiliary exhaust valve port and means for rendering said devices ineffective when the valve shaft is operated by one of said sets of driving devices. 70

7. In an explosive engine, the combination with a cylinder having a piston and a crank shaft connected thereto, said cylinder being provided with an inlet port and main and auxiliary exhaust ports, a valve controlling the auxiliary exhaust port and a separate valve controlling the inlet port, a 75 shaft for operating the inlet valve and two separate sets of driving connections for operating said shaft to open and close its valve at different times relatively to the reciprocation of the piston in the cylinder, of devices driven by the valve shaft for actuating the exhaust valve, means for alternatively connecting either of said sets of driving connections to the valve shaft, and co-operating controlling mechanism for rendering the exhaust valve actuating devices operative in respect to one set and inoperative in respect to the other set of the inlet valve driving devices. 80

8. In an explosive engine, the combination with a cylinder having a piston and a crank shaft connected thereto, said cylinder being provided with an inlet port and main and auxiliary exhaust ports, a valve controlling the auxiliary exhaust port and a 85 separate valve controlling the inlet port, a shaft for operating the inlet valve and two driving wheels loosely mounted on the valve shaft and operatively connected with the crank shaft, and mechanism for actuating the auxiliary exhaust valve, of a clutch member on the valve shaft adjustable into engagement with either of said driving wheels, a shiftable controlling member for rendering the exhaust valve actuating 90 mechanism alternately operative and inoperative and connections between said member and the clutch. 100

9. In an explosive engine, the combination with a cylinder having a piston and a crank shaft and provided with an inlet port and main and auxiliary exhaust ports, of valves controlling the inlet and auxiliary exhaust ports, a shaft on the inlet valve and double sets of driving connections between the crank shaft and valve shaft each including a member journaled on the valve shaft, a lever for operating the exhaust valve, means for rocking it, a controlling member for adjusting said lever into and out of operative engagement with the valve, a clutch member on the valve shaft coöperating alternatively with either of the driving members thereon and operating connections between the clutch and controlling member. 110

10. In an explosive engine, the combination with a cylinder having a piston and a crank shaft and provided with an inlet port and main and auxiliary exhaust ports, of valves controlling the inlet and auxiliary exhaust ports, a shaft on the inlet valve and double sets of driving connections between the crank shaft and valve shaft each including a member journaled on the valve shaft, a pivoted lever for operating the exhaust valve, means for rocking the lever, an adjustable guide block supporting said lever, a controlling member coöperating with the block to position the lever in respect to the exhaust valve and an adjustable member forming an operating connection between the inlet valve shaft and the separate driving members thereon.
11. In an explosive engine, the combination with a cylinder having a piston and a crank shaft and provided with an inlet port and main and auxiliary exhaust ports, of valves controlling the inlet and auxiliary exhaust ports, a shaft on the inlet valve and double sets of driving connections for effecting two cycle and four cycle operation of the engine and arranged between the crank shaft and valve shaft each including a member journaled on the valve shaft, a pivoted lever for operating the exhaust valve, a movable guide block supporting the lever, a cam on the valve shaft and a rod operated thereby and coöperating with the lever, a controlling

member for adjusting the guide block to move the lever into and out of operative position in respect to the valve and means for locking one or the other of the driving devices to the valve shaft. 35

12. In an explosive engine, the combination with a cylinder having a piston and a crank shaft and provided with an inlet port and main and auxiliary exhaust ports, of valves controlling the inlet and auxiliary exhaust ports, a shaft on the inlet valve and double sets of driving connections for effecting two cycle and four cycle operation of the engine and arranged between the crank shaft and valve shaft each including a member journaled on the valve shaft, a clutch member adapted to alternatively lock either of said driving members to the valve shaft, a cam on the latter, a tappet rod reciprocated by the latter and a lever operated thereby and adapted to coöperate with the auxiliary exhaust valve, an adjustable bearing member supporting the lever, a controlling member coöperating with said bearing member to adjust the lever relatively to the valve and a shifting member connecting the clutch and controlling member for simultaneous operation. 40 45 50 55 60
